UNITED STATES PATENT OFFICE.

WILLIAM T. ENSIGN AND STEVEN A. ALMIDA, OF CHICAGO, ILLINOIS.

TOY.

1,212,332.

Specification of Letters Patent. Patented Jan. 16, 1917.

Application filed April 14, 1916. Serial No. 91,192.

To all whom it may concern:

Be it known that we, WILLIAM T. ENSIGN and STEVEN A. ALMIDA, citizens of the United States, residing at Chicago, in the county of Cook and State of Illinois, have invented new and useful Improvements in Toys, of which the following is a specification.

This invention relates to improvements in toys, an object of the invention being to construct a toy in the form of an animated body having a roller or wheel journaled therein to contact with the surface upon which the body is supported, and to secure to the axle 10 of a roller or wheel, a flexible shaft, such as a spirally wound wire which, when turned between the fingers of the operator or by a mechanical device will revolve the shaft to rotate the wheel, causing the figure to move 15 in either a forward or rearward direction as desired.

It is a further object of the invention to produce a toy comprising a comparatively light body having a comparatively heavy 20 wheel arranged upon an axle which is journaled in bearings in the body and to attach to the axle a flexible shaft which when turned between the fingers of the hand of an operator or by means of a mechanical device 25 will revolve the wheel.

It is a still further object of the invention to construct a toy of a comparatively light body to provide the same with a wheel or roller that has its axle journaled in suitable 30 bearings in the body and to secure to the axle a flexible shaft, the axle being arranged at a slight angle with respect to the body to tilt or incline the roller so that the toy will be caused to travel in a direction away from 35 the operator who manipulates the same by turning the flexible shaft.

With the above and other objects in view the improvement resides in the construction, combination and arrangement of parts set 40 forth in the following specification and falling within the scope of the appended claims.

In the drawing: Figure 1 is a perspective view of a toy constructed in accordance with the present invention, Fig. 2 is a longitudinal 45 sectional view through the same, Fig. 3 is a transverse sectional view approximately on the line 3—3 of Fig. 2, and Fig. 4 is a bottom plan view of the device.

While in the drawing we have illustrated a toy having a body portion in the form of a mouse, it is to be understood that any other form of body may be employed so that the toy may be constructed to represent any animated body. The body 1 is constructed of comparatively light material, such for instance as papier mâché, thin metal or the like, and the said body is hollow or is formed upon its underface with a longitudinally extending groove. The walls to the opposite side of the groove at approximately the central portion of the body and adjacent the lower edge thereof are provided with openings which are not in a line, one being disposed above and forward of the other and these openings provide a bearing for a shaft 3, upon which is arranged a comparatively heavy wheel or roller 4. The axle at the end thereof arranged nearest the lower and rear portion of the body is extended through the body and has secured thereto a flexible member 5 which is preferably in the nature of a coiled wire, and this wire may be of any desired length.

In operating the toy the end of the flexible shaft is held between the fingers of the operator or attached to a mechanical device and turned or twisted, which movement will cause the rotation of the shaft and as a consequence turn the wheel or roller so that the body will be moved in either a forward or rearward direction.

By arranging the wheel or roller at an angle the toy will have a tendency to pull away from the operator, and thus compensate for the necessary tension upon the flexible shaft or wire.

From the above description taken in connection with the accompanying drawing, the simplicity of the device, as well as the advantages thereof will, it is thought, be perfectly apparent to those skilled in the art to which such invention appertains without further detailed description.

Having thus described the invention, what we claim is:

1. A toy including a body having an axle journaled in bearings therein, a roller upon the axle and adapted to be arranged upon a support for the body, and a flexible operating shaft secured to the axle.
2. A toy including a comparatively light

body, an axle journaled in bearing openings in the body, a comparatively heavy wheel secured to the axle adapted to rest upon the support for the toy, and a flexible shaft secured to the axle.

3. In a toy, a hollow body having angularly disposed openings, an axle journaled in said openings, a roller secured to the axle and resting upon the support for the toy,

and a flexible member connected to one of 10 the ends of the shaft for operating the shaft.

In testimony whereof we affix our signatures in presence of two witnesses.

WILLIAM T. ENSIGN.
STEVEN A. ALMIDA.
